ATTORNEY'S

UNITED STATES PATENT OFFICE.

CHARLES T. PRATT, OF CLAYVILLE, NEW YORK.

DESIGN FOR A SLIP-NIPPLE.

SPECIFICATION forming part of Design No. 25,709, dated June 30, 1896.

Application filed February 6, 1896. Serial No. 578,282. Term of patent 14 years.

To all whom it may concern:

Be it known that I, CHARLES T. PRATT, a citizen of the United States, residing at Clayville, in the county of Oneida and State of New York, have invented and produced a new and original Design for Slip-Nipples, of which the following is a specification, reference being had to the accompanying drawings, showing the same.

10 Figure 1 is a perspective view of a slip-nipple of my design. Fig. 2 is a central section of the same.

The leading feature of my design consists in the general swelled shape of the body of

15 the nipple, as shown, of substantially uniform

thickness of metal throughout its entire body, and having a circumferential enlargement *a* on its exterior surface midway between the ends of the nipple, and a corresponding depression *b* on its inner surface.

20

What I claim is—

The design for a slip-nipple herein shown and described.

In witness whereof I have affixed my signature in presence of two witnesses.

CHARLES T. PRATT.
